CLAIM

The ornamental design for a pool skimmer basket with a floating weir, as shown and described.

DESCRIPTION

FIG. 1 is a top perspective view of a first embodiment of a pool skimmer basket with a floating weir in a raised position, showing my new design;

FIG. 2 is a top perspective view thereof, illustrated with the floating weir in a lowered position;

FIG. 3 is a front elevational view of FIG. 1, the rear elevational view, left-side elevational view, and right-side elevational view all being identical thereto;

FIG. 4 is a top plan view of FIG. 1;

FIG. 5 is a bottom plan view of FIG. 1;

FIG. 6 is a cross-sectional view thereof, taken along line 6--6 of FIG. 4.

FIG. 7 is a top perspective view of a second embodiment thereof, illustrated with the floating weir in the raised position;

FIG. 8 is a top perspective view thereof, illustrated with the floating weir in the lowered position;

FIG. 9 is a front elevational view of FIG. 7, the rear elevational view being a mirror image thereof;

FIG. 10 is a left-side elevational view of FIG. 7, the right-side elevational view being a mirror image thereof;

FIG. 11 is a top plan view of FIG. 7;

FIG. 12 is a bottom plan view of FIG. 7; and,

FIG. 13 is a cross-sectional view thereof, taken along line 13-13 of FIG. 11.
